UNITED STATES PATENT OFFICE.

W. BRYENT, OF BOSTON, MASSACHUSETTS, ASSIGNOR TO DANIEL D. BADGER, OF NEW YORK, N. Y.

COMBINED RAILROAD-TRACK AND CAST-IRON PAVEMENT.

Specification of Letters Patent No. 20,620, dated June 22, 1858.

To all whom it may concern:

Be it known that I, WALTER BRYENT, of Boston, in the county of Suffolk and State of Massachusetts, have invented a new Combined Cast-Iron Railway and Pavement for Streets; and I do hereby declare that the following is a full and exact description thereof, reference being had to the accompanying drawings, making part of this specification, Figure 1 being a plan of a portion of the tracks and intervening pavement for a double-track city-railway constructed in my improved manner; Fig. 2, a transverse vertical section of the same. 15 Like letters designate corresponding parts in both the figures.

I cast the track and intervening pavement in large sections, each section including the reticular pavement B, and the rails A, A, 20 on both sides thereof, and forming one entire piece. The width of each section, of course, depends on the gage of the railway; and the length may be such as to be most convenient for casting and laying down, say 25 nearly the same as the width. The form of the rail is not material, nor do I confine myself to any exact form of the pavement, although the reticular construction, with diagonal cells or meshes, substantially as 30 represented in the drawings, is preferred to any yet devised. In this, the intersections f f of the metallic web, rise in projections higher than the intermediate portions e, e, 35 in the manner shown; so that the proper degree of roughness is secured, to prevent the slipping of the horses, while the general surface, when the pavement is embedded in gravel or cement, is level, and offers but slight resistance to the passage of carriage 40 wheels.

One end of each section of the track rails A, A, has a tenon a; and the other end is provided with a corresponding mortise b; so that when two adjacent sections are 45 placed together, the tenon of one rail fits

into the mortise of the contiguous rail, and thus strongly holds them together.

The pavement portions of the adjacent sections are interlocked by means of tongues, or ledges, c, d, cast in the half cells or meshes of their edges. The alternate tongues c, c, on each border, are near the bottom of the pavement, and the intermediate tongues d, d, are nearer the top; and they are so arranged that the tongues d, d, of one section, may slide closely over the tongues c, c, of the adjacent section, and thereby firmly connect the sections. In this way, when the pavement and tracks are once firmly laid down, the whole compose one firm, immovable surface.

Between the inner rails of a double-track railway, the space is, or may be, covered with sections of pavement C, similar to the pavement B, which connects the rails. 65 These sections may be simply embedded between the tracks, or may be locked to the rails in any convenient manner. Other sections of pavement may be placed outside of the railway, till the whole street is paved in 70 a similar manner.

What I claim as my invention and desire to secure by Letters Patent, is—

1. The combination of a cast-iron pavement and railway, cast and united together 75 in suitable sections, substantially as herein described.

2. I also claim the combination of the tenons a, a, mortises b, b, on the ends of the rails, and the alternate over and under 80 lapping tongues c, d, on the edges of the pavement, substantially as specified, for the purpose of interlocking the adjacent sections of the combined pavement and railway.

WALTER BRYENT.
